UNITED STATES PATENT OFFICE.

GEORGE D. HARTLETT AND WILLIAM A. WHEELER, OF NEW CANAAN, CONNECTICUT,
ASSIGNORS, BY DIRECT AND MESNE ASSIGNMENTS, OF ONE-HALF TO SAID GEORGE
D. HARTLETT AND ONE-HALF TO CHARLES E. POWELL, OF STAMFORD, CON-
NECTICUT.

WINDOW-SCREEN.

1,069,251.

Specification of Letters Patent.

Patented Aug. 5, 1913.

Application filed March 23, 1911. Serial No. 616,401.

To all whom it may concern:

Be it known that we, GEORGE D. HARTLETT and WILLIAM A. WHEELER, citizens of the United States, residing at New Canaan, 5 in the county of Fairfield and State of Connecticut, have invented certain new and useful Improvements in Window-Screens, of which the following is a specification.

Our said invention consists in various improvements in the details of construction of screens for windows, of that type known as roller screens, wherein the screen may be rolled up, or extended, to accommodate any extent of window opening, and it has for 15 its object to provide such a screen structure the operation of which will not only be efficient but practically noiseless and free from rattle, all as will be hereinafter more fully described and claimed.

20 Referring to the accompanying drawings which are made a part hereof and on which similar reference characters indicate similar parts, Figure 1 is a view of a window with the lower sash partly opened and the opening covered with a screen mounted on supports of our improved construction, Fig. 2 a horizontal section on the dotted line 2—2 in Fig. 1, Fig. 3 a vertical section on the dotted line 3—3 in Fig. 1, Fig. 4 a detail 25 view of the rack and pinion separately, showing the rack in section and the pinion in elevation, and Fig. 5 a detail view illustrating a modification.

In said drawings the portions marked A 35 represent the roller upon which the screen is mounted, B the screen and C a metal guard, or casing, surrounding the roller.

It will be understood, of course, that the window structure, including the frame, sash 40 and other parts, may be of any form, that shown being used merely to illustrate the use of the invention.

The roller A is preferably a metal tube of appropriate size and a metal shaft *a* extends from end to end through the same and is connected thereto by a coiled spring *a'*, one end of which is inserted in a transverse perforation in said shaft and the other end of which is connected to said tube. 45 The ends of shaft *a* are journaled in bearings in the ends of casing C. The screen B is of any preferred style or make and is attached at one end to said roller A and at

the other end to the window-sill by means of a metal strip or shoe *b*.

55 The guard, or casing C, is preferably of sheet metal and of a semi-cylindrical form adapted to surround the roller A and inclose the screen B thereon. Its ends contain bearings for the ends of shaft *a*.

60 Metal housings 10 are secured to the sides of the window-frames, said housings being of sheet metal pressed or bent to the form best illustrated in Fig. 2, consisting of a base adapted to rest against the side of the 65 casing, a back side adapted to extend at right angles with a base and parallel with the plane of the window, a front side extending outwardly for a distance parallel with the back side and then turned inwardly 70 for a distance to form a flange opposite to and parallel with the base of said housing. A non-metallic rail 11 is mounted in the outer part of said housing between said in-turned flange and its base and a non-metallic 75 bar 12 is mounted on its back side. Said non-metallic bars 12 are formed with a series of perforations or notches adapted to receive the teeth of the pinions and serve as rack-bars. The shaft *a* extends beyond 80 the ends of roller A and has pinions 13 rigidly secured thereon which are adapted to mesh with the notches in said bars 12. Said pinions 13 and bars 12 are both preferably 85 of fiber, or other non-metallic substance of a similar character, whereby the operation will be noiseless. It may be found that one or the other of said parts may be of metal, but we regard it as essential that at least one of said parts be made of non-metallic 90 substance, as one of the leading purposes of our invention is to provide a structure of the character named, the operation of which will be practically noiseless.

95 A rod 14 extends longitudinally through a tubular formation on the upper edge of casing C and a rod 15 through a similar formation on the lower edge of said casing. The outer ends of said rods extend beyond the ends of said casing and are provided 100 with rollers 16 of rubber, or similar non-resonant material. Said rollers fit snugly in the way formed between the adjacent faces of the bars 11 and 12 in the housing 10. It will be noted by an examination of Fig. 2 105 that bar 12 is of a width to extend beyond

the line of the inturned outer side of housing 10 and that the notches forming the rack-bar are beyond said point so that the pinions 13 may engage with said notches 5 and clear said housing. The rods 14 and 15 with the rollers 16 extend to within the housing and between the bars 11 and 12, as shown.

In Fig. 5 we have shown the outer ends 10 of rods corresponding to the rods 14 and 15 turned at right angles, with a roller 17 thereon adapted to operate between adjacent faces of a bar set against the base of housing 10 and another set against the inner face 15 of the inturned flange. This is a modification of the form shown in Fig. 2 and one of the obvious changes that may be made in the structure without departing from our invention.

20 In use the normal position of the casing C is at the lower end of the runs in housings 10 or practically resting upon the window-sill where the screen will be completely enclosed by said casing. After the window is 25 raised casing C is also lifted until the roller A is opposite end lower rail 20 of the sash, the rollers 16 on the ends of rods 14 and 15 serving to guide and keep the casing in vertical position. The teeth of the pinions 13 30 engaging with the notches in bars 12 serve to rotate said pinions and through them the shaft *a* which serves to wind the spring *a'* and exert a tension upon the screen B, keeping it taut and straight.

35 Having thus fully described our said invention, what we claim as new and desire to secure by Letters Patent, is:

1. A window screen comprising a roller, a screen mounted on said roller one edge of 40 said screen attached to one side of the window opening, pinions on the axis of said roller, rack-bars on each side of the window opening with which said pinions engage, a guard rail adjacent to each of said rack-bars, a shield or casing mounted to cover the roller, rods extending through the edges of 45 said casing to between the rack-bars and guard rails, and rollers mounted on the ends of said rods and adapted to roll in the space, 50 between said guard rails and said rack-bars, substantially as set forth.

2. A window screen comprising a casing, a roller journaled within said casing, ways in the adjacent sides of the window frame, 55 rollers carried by said casing and adapted to run in said ways, wheels mounted on the axle of said roller and adapted to engage with rack bars on the window frame for rotating said axle, a screen attached at one 60 end of said roller and at the other end to

one side of the window opening, substantially as set forth.

3. A window screen comprising a roller, means for supporting said roller to be moved vertically in the window frame, an axle running through said roller and carrying wheels on its outer ends adapted to engage with rack bars on said window frame and operate said axle, said bars, rollers carried on the outer ends of the structure adapted to engage in said ways for guiding and holding said roller, and a screen attached at one end to said roller and at the other end to one side of the window opening, substantially as set forth.

4. A window screen comprising a casing, a roller journaled in said casing, vertical ways at the sides of the window opening, rack-bars forming part of said ways, pinions on the ends of the roller shaft engaging said rack-bars, one of said engaging parts being non-metallic, guide rollers on said casing, engaging said ways, and a screen attached at one edge to said roller and at the other edge to one side of the window opening, substantially as set forth.

5. A window screen comprising a casing, guide rollers on the opposite sides and ends of said casing, ways on each side of the window opening formed to receive said rollers, 90 rack-bars alongside said ways, a tubular roller in said casing, a shaft in said roller journaled in said casing, a spring connected at one end to said shaft and at its other end to said roller, pinions on the ends of said shaft engaging said rack-bars, the guide rollers engaging and sliding in said ways on opposite sides of said pinions, and a screen attached at one end to said roller and at the other end to one side of the window 100 opening, substantially as set forth.

6. A window screen comprising a casing carrying non-metallic guide rollers on its corners, ways on the sides of the window opening in which said rollers are mounted 105 to run, a roller in said casing, pinions on the shaft of said roller of non-metallic material engaging ways alongside the window opening, and a screen mounted on said roller and connected at one edge to one side of the 110 window opening, substantially as set forth.

In witness whereof, we have hereunto set our hands and seals at Washington, District of Columbia this 15th day of March, A. D. nineteen hundred and eleven.
